AUTOMATIC SYSTEM FOR SUPPLYING ALKALI AND DETERGENT TO COMMERCIAL LAUNDRY WASHING MACHINES

Herbert A. Hambro, Milton, Mass., assignor to The Veritas Company, Inc., Medway, Mass., a corporation of Massachusetts

Filed Nov. 6, 1962, Ser. No. 235,641
5 Claims. (Cl. 222—1)

This invention relates to a method of automatically feeding cleansing ingredients to the washing machines or wash wheels of industrial laundries, and pertains more particularly to a novel method of delivering liquid ingredients or supplies, in controllable proportions, from storage tanks directly to the wash wheels.

The supplies or ingredients are those customarily used by industrial or commercial laundries, namely, an alkali such as caustic soda mixed with a silicate, such as sodium silicate, and a non-ionic or anionic detergent, but these ingredients are stored and delivered as liquids rather than as powders.

The principal purpose of the invention is to provide a completely automatic monitored system for feeding the supplies, in the desired quantities and proportions, from relatively large storage tanks which may be conveniently filled from tank trucks, directly to the wash wheels in the wash room, after first mixing the alkali and silicate in a separate tank or compartment and then delivering that alkali mix and the concentrated detergent through separate supply lines to the wash wheel.

More specifically, the objects of this invention are to lower supply costs and save washing time by using liquid alkali which is less expensive than powdered alkali in the quantities required, and by accurately controlling the volume of each of the liquid ingredients according to the desired washing formula; to lower production expense by eliminating manual handling, measuring and waste of conventional powdered ingredients, and by shortening the washing cycle inasmuch as no time need be allowed for dissolving powders, thereby lessening mechanical wear and extending the life of the washed garments; and to permit the essential controls of the system to be operated by well known types of sequence timers which have heretofore been customarily used in circuit breaker distribution panels, to control the timing of the washing cycle of a battery of wash wheels in industrial laundries.

Further advantages of the automatic supply system will become apparent from the following description of the improved method, as diagrammatically illustrated on the accompanying drawings, in which:

FIG. 1 is a schematic diagram of the preferred system, as used in delivering the liquid detergent and the liquid alkali mix through separate supply lines to a battery of wash wheels, in measured quantities;

FIG. 2 is a more detailed diagram of that part of the system in which the alkali or caustic ingredient and the silicate ingredient are combined and mixed with water, and then delivered to the alkali mix storage tanks;

FIG. 3 is a detailed diagram of the piping system for supplying the alkali mix to the wash wheels; the piping system for supplying the detergent being essentially similar thereto;

FIG. 4 is a diagram of a compressed air piping system for servicing air-operated control valves in the liquid supply systems; and

FIG. 5 is a diagram of the electric control system for regulating the caustic-silicate mix and the supply of the detergent and alkali mix to the wash wheels.

In accordance with the method of this invention, the basic liquid ingredients are stored in large-sized vented tanks (or a single compartmented tank) providing reser-

2

voirs for detergent, alkali mix, silicate and caustic; such tanks preferably being so located that the three storage reservoirs for the basic ingredients may be filled from tank delivery trucks, and that the detergent and the alkali mix may be conveniently pumped to the dispensers in the wash room, through separate supply lines, as indicated in FIG. 1 and FIG. 3.

The liquid silicate and caustic are piped from their respective reservoirs to proportioning pumps, labeled silicate pump and caustic pump in FIG. 2; these pumps being of well known and commonly used types, such as those sold under the trade name Proportioners Treet-O-Unit and operated by compressed air. The respective pumps may be adjusted to supply any desired ratio of caustic soda and silicate, to produce a mixture ranging from sodium metasilicate to sodium orthosilicate.

The pipe lines leading from the respective reservoirs to the proportioning pumps, and from said pumps to the water supply piping, may be equipped with gate or plug valves at 11 and 12, strainers at 13, T's at 14, check valves at 15 and other fittings or unions not pertinent to the present invention, as indicated by the plumbers' symbols on the drawings.

The water supply line for cold fresh water leads through 25 a check valve 16 and gate valves 17 to a control meter associated with a solenoid controlled regulating valve 18; thence to a hydraulic valve 19 and through another check valve 20, to the connections from the respective proportioning pumps; and thence past a pressure gauge 21, 30 through strainers, to a mixing chamber 22 (FIG. 1) and to the alkali mix reservoir. Said reservoir is provided with a float 23 (FIG. 1) for actuating a float switch 24 (FIG. 2) in said chamber, which automatically stops the operation of the alkali combining system when the mix reservoir is filled to a predetermined level.

The float switch, the control meter and its said solenoid valve, and solenoid valves of the respective proportioning pumps are in circuit with each other and with a distribution panel, as indicated at the left hand portion of the 40 schematic wiring diagram of FIG. 5. That circuit may also include an electronic conductivity meter for registering the alkalinity of the alkali mix, and an alkali level alarm, as indicated. The circuit breaker distributor panel of FIG. 5, may be a standard type of sequence timer heretofore used in controlling the successive operations of 45 washing, rinsing and spin-drying in commercial clothes washing machines, in predetermined sequence—with such additional contacts as may be needed for programming the alkali mix and detergent supply systems also indicated in FIG. 5 and described below.

As indicated generally in FIG. 1, concentrated liquid detergent is fed from the detergent reservoir by either of the alternate pumps 31, 32, to a header pipe 33 for a series of automatic dispensers 34 for a battery of washers 55 1, 2, 3, 4, 5 and 6, or optionally through a meter 35 to a header pipe 36 for manual-controlled supply to the same battery of wash wheels.

Similarly, liquid alkali is pumped from the alkali mix reservoir by pump 37 or pump 38 to a header pipe 39 for a series of automatic dispensers 40 for the battery of wash wheels, or optionally through a meter 41 to a header pipe 42 for manual feeding to the wash wheels.

The automatic dispensers for detergent and alkali are arranged to be filled to capacity and then to be discharged and refilled, thus regulating the quantity of each liquid to be supplied to the washers; and the alkali dispensers 40 are normally larger (e.g. holding 8 gallons each) than the concentrated detergent dispensers 34 (e.g. holding 1 quart each), for industrial washing machines.

The piping of the alkali supply system is diagrammed in greater detail in FIG. 3. The pipes 43, 44 from the alkali mix reservoir to the respective pumps 37 and 38

are preferably equipped with gate valves 45 for manual shut-down when needed, and with pressure gauges 46; and the pumps are associated with motors 47 and 48, respectively, actuated by solenoid switches 49 and 50 in the control circuit of FIG. 5. The extra pump is preferably provided for stand-by purposes, in the event that the other pump fails to operate correctly.

Each pump has a delivery line 51 and 52 respectively, leading to a common supply pipe 53, each provided with a check valve 54 and a gate or globe valve 55; and each pump also connects to a return line 57 and 58, each having a strainer 59 and orifice plate 60, for feeding excess alkali back to the reservoir when the automatic dispensers are filled and the check valves in the supply lines are closed. Pressure gauges 61 may be connected in the outlets of said pumps.

Supply pipe 53 leads to the header pipes 39 and 42, as aforesaid, and the supply line may have a pressure gauge 62 and a pressure switch 63. Manual valves are preferably provided, as indicated, in the lines to the respective header pipes, so that the system may be regulated for automatic or for manual feeding of the alkali mix to the washers; and the header 42 has the aforesaid meter 41 and, preferably, a strainer 64.

Each automatic dispenser 40 is filled from header 39 by a separate supply line 65 having gate and check valves 66 and 67; and each, after being filled, discharges to an individual wash wheel, through a relief valve 68 and a transparent plastic pipe section 69. The filling and discharge of dispenser 40 is controlled by a three way air valve 70 (FIG. 4) which is actuated by the electrical control system of the sequence timer.

The supply system for the concentrated liquid detergent is essentially the same as that just described in connection with the alkali mix supply system of FIG. 3, which shows in broken lines the connection of the automatic detergent dispenser 34 of FIG. 1 to the supply line 65 leading to the individual wash wheel. As previously explained, the detergent and alkali are not mixed together until the mixture is to be discharged into the respective wash wheels, thereby avoiding chemical breakdown of those supplies which would be likely to result upon standing intermixed in a supply line.

The detergent dispenser 34 is also controlled by a three-way, air-operated valve 75 (FIG. 4) actuated by the electrical control system; and it will be understood that the air valves 70 and 75 regulate the filling, discharge and refilling of the automatic dispensers in timed sequence, and that the alkali dispenser and detergent dispenser, for each wash wheel, are actuated simultaneously or separately, as desired and programmed.

The piping for the air pressure system for operating the diaphragm valves of the automatic supply system and the optional manual supply system of the liquid ingredients for the washers, is diagrammed in FIG. 4. The supply of compressed air enters a pipe 81 equipped with gate valves 82 and a strainer 83, and having a branch line 84 leading through a globe valve 85 to a relief valve 86, and another branch line 87 leading through a reducing valve 88 and a globe valve 89 back to main line 81 near an adjustable pressure valve 90 having a gauge 91. The air line then branches to the air valves 70 and 75 of the respective automatic dispensers 40 and 34 for each wash wheel, and to the manually actuated air valves 73 and 92 for regulating the supply of alkali and detergent respectively by hand. It will be understood that air valve 92 would be operated by a separate push button 93.

It will be understood that the electric circuits diagrammed in FIG. 5 are controlled by conventional switches on a monitoring panel, the operation of the sequence timer being regulated by a conventional programming chart.

The automatic flow system for supplying liquid ingredients to the wash wheels of industrial laundries, as herein disclosed, conveniently and efficiently achieves the objectives of this invention, as previously set forth. Substantial economies are achieved with increased output in a shorter time period, by utilizing stored liquid alkali, automatic measuring controls which precisely regulate the washing formula, thereby eliminating manual mixing, spillage, and danger to personnel. It has been found that seven loads of industrial wash may be washed, with uniform quality, by the use of this completely automatic method, in the time normally required for six loads, per machine per day, thus increasing productivity of the laundry as well as reducing cost of operation.

I claim:

1. A method of automatically supplying cleansing ingredients to the wash wheels of an industrial laundry, which comprises the steps of storing a silicate, a caustic and a concentrated detergent, each in liquid form, in separate reservoirs, fillable from tank trucks; providing a fourth separate reservoir for a mixture of the silicate and caustic; pumping a mixture of a metered quantity of water, a proportioned quantity of the liquid caustic and a proportioned quantity of the liquid silicate to said fourth separate reservoir, to provide an alkali mix; pumping the alkali mix from its reservoir through a flow line to a wash wheel area; pumping the concentrated detergent from its reservoir through a separate flow line to said wash wheel area; dispensing a predetermined quantity of said alkali mix and said concentrated detergent from said respective flow lines into said wash wheel; and electrically controlling the operating of said pumping steps.

2. A method as described in claim 1, including the further step of electrically controlling the dispensing step in time sequence with relation to the electrical control of said pumping steps.

3. A method as described in claim 2, including the further steps of pumping the alkali mix and the detergent to separate refillable dispensers of predetermined capacity, separately dispensing the alkali and detergent from the dispensers to the wash wheel, refilling said dispensers, and electrically controlling the filling, dispensing and refilling of said dispensers by said electrical controlling step.

4. A method as described in claim 3, including the further step of controlling the filling, dispensing and refilling of said dispensers by valves regulated by said electrical controlling step and actuating said valves by compressed air.

5. A method as described in claim 3, including the further step of providing alternative supply lines and manually controlled valves therefor for optionally dispensing the alkali mix and the detergent from said dispensers to said wash wheels.
